CLAIM

The ornamental design of a refuse hauling vehicle, as shown and described.

DESCRIPTION

FIG. 1 is a perspective view of a refuse hauling vehicle showing my new design with its dumpster tipping arm assembly in its elevated disposition;

FIG. 2 is a left side elevation thereof; the right side being the same as the left side shown;

FIG. 3 is a rear view thereof;

FIG. 4 is a front view thereof with its dumpster tipping arm assembly in its lowered disposition; and,

FIG. 5 is a top plan view thereof.
